UNITED STATES PATENT OFFICE.

HARRY W. SCHWETTMAN, OF CINCINNATI, OHIO, ASSIGNOR TO THE GRUEN WATCH COMPANY, OF CINCINNATI, OHIO, A CORPORATION OF OHIO.

DESIGN FOR A WRIST-WATCH CASE.

Application filed May 26, 1924. Serial No. 9,707. Term of patent 3½ years.

To all whom it may concern:

Be it known that I, HARRY W. SCHWETTMAN, a citizen of the United States of America, and a resident of Cincinnati, in the county of Hamilton and State of Ohio, have invented a new, original, and ornamental Design for a Wrist-Watch Case, of which the following is a specification, reference being had to the accompanying drawing, forming part thereof.

Fig. 1 is a plan view of a wrist watch case, showing my new design.

Fig. 2 is a side elevation of a watch case showing my new design.

I claim:

The ornamental design for a wrist watch case, as shown.

HARRY W. SCHWETTMAN.
